FIG. 4.

UNITED STATES PATENT OFFICE.

PERSIE JULIAN LATHAM, OF LONG BRANCH, NEW JERSEY.

SHEET-PILEING.

1,001,963.

Specification of Letters Patent. Patented Aug. 29, 1911.

Application filed January 11, 1911. Serial No. 602,118.

To all whom it may concern:

Be it known that I, PERSIE JULIAN LATHAM, a citizen of the United States, residing at Long Branch, Monmouth county, New Jersey, have invented certain new and useful Improvements in Sheet-Piling; and I do hereby declare the following to be a full, clear, and exact description of the invention, such as will enable others skilled in the art to which it appertains to make and use the same.

This invention relates to certain improvements in sheet piling, or the like; and the objects and nature of my invention will be readily understood by those skilled in the art in the light of the following explanation of the accompanying drawings illustrating what I now consider to be my preferred embodiments from among other formations and arrangements within the spirit and scope of my invention.

An object of the invention is to provide an improved pile or beam capable of interlocking, in various relations and positions with adjacent members against transverse strain, and so formed as to give the maximum strength with the use of a minimum amount of material in the construction thereof.

A further object of the invention is to provide certain improvements in interlocking sheet piling to attain simplicity, strength, durability, economy in construction, and varied adaptability for general use.

The invention consists in certain novel features in construction and in formations and arrangements as more fully and particularly set forth hereinafter.

Referring to the accompanying drawings;—Figure 1, is a perspective view of a number of the construction elements of my invention employed as sheet piling. Fig. 2, is a cross section on the line 2—2, Fig. 1. Fig. 3, is a perspective view showing several of said elements of my invention assembled and interlocked to provide a different form or arrangement from that appearing in Fig. 1. Fig. 4, is a perspective view of the preferred metal reinforcement for the pile or construction element when made of concrete, the pile being outlined by dotted lines, the reinforcement being shown in full lines. Fig. 5, is a top plan illustrating va-

rious arrangements that can be followed in 55 interlocking the piles or construction elements.

The construction element of my invention can be formed of any desired length according to the requirements of any particular 60 instance or use. Also the particular requirements will in each instance to a more or less extent determine the exact formation, thickness and width of the element. In the particular example illustrated, each 65 element is comparatively wide with respect to its thickness, and throughout both longitudinal edges is similarly formed with longitudinal ribs or tongues and intervening grooves or sockets, the longitudinal intervening sockets being similar in cross sectional formation to the ribs, that is, of the same angle or of the same radius or curvature should the parts be curved or rounded. I also prefer to form the opposite edge portions of the element with such ribs or 70 tongues along the opposite side faces thereof, so that either edge socket of any element can fit and receive any one of said side face ribs of another element when said elements 75 are arranged at right angles to each other, as when forming a corner.

In the drawings, I show each element formed with a central longitudinal body or web 1, of a uniform thickness throughout 85 the length of the element. The opposite longitudinal edge or interlocking portions of the element are alike and each consists of a pair of diverging flanges or jaws 2, extending throughout the length of the element and forming the intervening longitudinal socket or groove 3. The two tongues 2, diverge at an angle of ninety degrees and hence form the intervening ninety degree triangular socket 3. Each tongue 2, is 90 flat at its longitudinal end edge and said flat end face forms ninety degree angles with the two flat side faces of the tongue or flange. Each tongue diverges from the plane of the web or body of the element at 100 an angle of forty five degrees, in the particular example illustrated, and hence each tongue forms a longitudinal ninety degree triangular rib 20, at the end of the element and forming one side wall of the triangular 105 socket 3, and also forms a longitudinal ninety degree triangular rib 21, at the adjacent side face of the element.

The two approximately similar longitudinal sockets 3, at the opposite end edges of the element, each formed by a pair of the ribs 20, are both of a form to snugly receive any one of the four ribs 20, or any one of the four ribs 21 of an element whether said ribs are formed by the four diverging rectangular flanges or tongues 2, of the element or are otherwise formed at the opposite edge 10 portions of the element.

Construction elements when thus made with approximately Y-shaped end edges can be used for various construction purposes with the elements interlocking at their edges 15 against lateral displacement. The edge formation is such that where the elements are being laid to form a straight line or in continuation of each other, as in Fig. 2, for instance, every alternate element will be 20 offset from the line of the intervening elements, and each element doubly interlocks with each abutting element in that one of its ribs 20, enters a socket 3, of the abutting element and one of the ribs 20, of the abutting 25 element fits a socket 3, of the first named element and forms elongated zig-zag joints between the elements, whereby maximum tightness against leakage is attained as well as maximum strength.

30 I prefer to form the sockets and ribs triangular in cross section with flat faces arranged at about ninety degree angles, whereby said flat faces of meeting elements squarely abut and resist the tendency of 35 elements to rock on each other at the joints in resisting transverse strains.

Construction elements of the general design or formation described are of peculiar utility for use in hydraulic engineering 40 work, as well as for retaining walls, foundations, bridge work and in other construction work. For instance, in Fig. 1, I show a line of the elements interlocking to form a wall as for beach protection, or a jetty, or to form 45 a retaining wall. When so used, the elements are sunk in the sand or soil either by driving, "jetting" or pumping as will be readily understood by those skilled in the art. Where the elements are to be thus sunk 50 or buried their lower ends are usually beveled off, see 22, to facilitate the sinking process and to cause the elements to bear tightly against each other.

By employing the side ribs 21, of approximately 55 the same formation as the end sockets 3, the elements can interlock in forming corners and can be readily fitted together to form inclosures as shown by Figs. 1, 3 and 5, and to resist lateral pressure. Also, if so 60 desired, corner protecting posts or piles such as 4, Fig. 5, can be employed at corners to brace and interlock the two elements forming the corner against inward and outward strains and to enable the inner flanges of said 65 elements to squarely abut, and to protect the

end edges of said elements against exterior pressure as well as blows and damage.

The formation of my construction element is such that it can be made of concrete, cement, or the like to great advantage and 7 utility. The design is such that the material is so distributed as to gain maximum strength and minimum use of material.

I have designed an advantageous metal reinforcement where concrete is to be employed for the purpose of distributing the strain on any flange 2, throughout the element. I show such metal reinforcement in Fig. 4, wherein metal rods 5, are arranged longitudinally within the element in the flanges 2, respectively, while spaced longitudinal metal rods 50, are arranged in the body or web 1. These various rods are tied together at intervals throughout the length of the element by a series of transverse trusses or wire bindings in such a manner that lateral strain on any one of the rods 5, will be resisted by said wire bindings and thus distributed to all of the longitudinal rods. Each wire binding is coiled around each rod 5, and extends directly between the rods 5, at each end of the element, see transverse lengths 6, and from one rod 5, the wire length 60, extends to the adjacent rod 50, and is coiled around the same and from thence extends to the corresponding rod 5, at the other end of the element bearing against but not coiled around the other rod 50, to form a truss between said rods 5. The other wire length 61, also extends in a similar manner between the other two corresponding rods 5, and is coiled on one rod 50, and bears against the other rod 50, to form a truss. The concrete element having its interlocking flanges thus reinforced and trussed to distribute the strain on any flange throughout the remainder of the element presents a structure of great strength and durability, and economy in construction and use because of comparative lightness and convenience for handling and minimum amount of material employed.

Where it is desired to form a water tight wall with the sheet piling disclosed, wooden beads or strips can be placed in the molds in which the concrete piles are to be formed so that said strips will be located at the apexes of certain of the ribs 20. When the piles are laid and interlocked, these wooden strip can be withdrawn leaving cavities a, Fig. 2, at the apexes of the sockets 3, and ribs 20, fitting therein, into which any suitable water proof elastic cement or sealing compound can be poured, as will be readily understood by those skilled in the art. As at present advised, I do not wish to limit all features of my invention to the sheet piling or construction element having its ribs and intervening sockets necessarily of angular formation so long as the formation of the

ribs is approximately the same as that of the sockets to permit any socket of a pile to receive any rib of the adjacent pile, and furthermore I do not wish to limit all features of my invention to providing the interlocking sheet pile element with the side ribs 21, and I also wish it understood that the element of my invention is adaptable for varied uses in construction and engineering work and my invention is not limited in this particular.

It is evident that various changes, modifications and variations might be resorted to without departing from the spirit and scope of my invention and hence I do not wish to limit myself to the exact disclosures hereof.

What I claim is:—

1. A sheet pile element, or the like, having approximately similar longitudinal end edges for interlocking with adjacent elements, each edge having a pair of longitudinal ribs and an intervening longitudinal socket, the ribs and sockets corresponding in cross sectional formation.

2. A construction element for interlocking sheet piling, and the like, having its longitudinal end edges correspondingly formed with diverging longitudinal flanges and intervening longitudinal sockets.

3. A construction element for interlocking sheet piling, and the like, having a comparatively wide thin body or web and diverging longitudinal edge flanges forming ribs and an intervening socket.

4. A construction element having longitudinal edge flanges diverging about at an angle of ninety degrees to form an intervening longitudinal socket.

5. A construction element having its opposite longitudinal edge portions correspondingly formed, each edge portion having longitudinal ribs at both sides thereof, and a pair of longitudinal ribs at the end

thereof forming an intervening longitudinal socket.

6. A construction element at its opposite longitudinal edge portions formed with correspondingly shaped diverging flanges having rectangular corners and flat faces and forming intervening rectangular sockets. 50

7. A concrete, or cement construction element for interlocking sheet piling and the like having edge flanges, longitudinal reinforcing rods arranged in said flanges and at intermediate points in the body of said element, and transversely arranged truss forming ties between said rods, substantially as described. 55

8. A concrete or cement construction element formed at its opposite longitudinal edges for interlocking with adjacent members and having longitudinal reinforcing rods arranged at said edges and at intermediate points, and series of transversely arranged truss forming metal ties uniting 60 said rods for distributing the strain on any one of said end rods to the other rod and throughout the elements. 65

9. A concrete or cement construction element having longitudinal flanges at its opposite edges for interlocking with adjacent elements, longitudinal reinforcing rods in said flanges, and truss forming ties between said rods and arranged at intervals throughout the element and forming trusses transversely of the element from each end rod to the corresponding end rod to the opposite edge of the element, said ties being coiled around the rods. 70 75

In testimony whereof I affix my signature, 80
in presence of two witnesses.
